(57) **CLAIM**

The ornamental design for a stand for electronic device, as shown and described.

DESCRIPTION

FIG. 1 is a perspective view of front, top and right side of a stand for electronic device showing my new design; FIG. 2 is a perspective view of rear, bottom and right side thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a first reference perspective view of usage thereof; FIG. 10 is a second reference perspective view of usage thereof;

FIG. 11 is a perspective view of a front, top and right side showing an alternate position;

FIG. 12 is a perspective view of rear, bottom and right side showing the alternate position thereof;

FIG. 13 is a front view showing the alternate position thereof;

FIG. 14 is a rear view showing the alternate position thereof;

FIG. 15 is a left side view showing the alternate position thereof;

FIG. 16 is a right side view showing the alternate position thereof;

FIG. 17 is a top view showing the alternate position thereof; FIG. 18 is a bottom view showing the alternate position thereof;

FIG. 19 is a first reference perspective view of usage showing the alternate position thereof; and,

FIG. 20 is a second reference perspective view of usage showing the alternate position thereof.

The broken lines show portions of the article or environment that form no part of the claimed design.

1 Claim, 16 Drawing Sheets
